CLOSURE CAP

Stanley J. Goldberg, Chicago, Ill., assignor to Aerosol Research Company, a corporation of Illinois

Application November 30, 1956, Serial No. 44,004

Term of patent 3½ years

(Cl. D58—26)

Fig. 2 is a top plan view thereof;

Fig. 3 is a bottom plan view thereof;

Fig. 4 is a side elevational view, thereof looking at the cap as positioned in Fig. 2;

Fig. 5 is a side elevational view of the cap as positioned in Fig. 3; and

Fig. 6 is a sectional view taken along the lines 6—6 in Fig. 2.

I claim:

The ornamental design for a closure cap, substantially as shown.
